UNITED STATES PATENT OFFICE

CHARLES L. MOYER, OF CHICAGO, ILLINOIS, ASSIGNOR TO QUALITY HARDWARE AND MACHINERY CORPORATION, OF CHICAGO, ILLINOIS, A CORPORATION OF ILLINOIS

GRIPPER MECHANISM

Application filed August 29, 1929. Serial No. 389,113.

This invention relates to gripper mechanism particularly, although not exclusively, to gripper mechanism for use with paper machines such as printing, signature and book making machines and the like, and is especially useful in high speed machines where long runs are made and when it is desired to operate for long periods of time without having to stop the machine for re-
10 pairs or adjustment.

The invention further contemplates a gripper mechanism which is readily adaptable to any kind of paper or like machine.

An object of the invention is to provide
15 a gripper mechanism which will automatically and accurately grip sheets or piles of paper of varying thicknesses and positively move the same away from the feeding mechanism and release such paper sheets or piles
20 at the desired point.

Another object of the invention is to provide a gripper mechanism for high speed machines having a minimum number of parts and one which is so constructed as to
25 continue in operation for long periods of time without repair or adjustment.

A further object of the invention is to provide a gripper mechanism which is fast in its operation, which is accurate in its
30 gripping mechanism and which is susceptible of long and continued use.

Generally speaking, the gripper mechanism consists of a plurality of rotary carriers arranged adjacent a feed mechanism
35 which carriers have associated therewith gripper fingers for gripping material delivered to the carriers by feed mechanism and which grippers are actuated into gripping and releasing position by a rock shaft
40 passing through the rotary carriers and actuated by a tumbler which cooperates with spaced curved flanges so that there is a minimum amount of wear on the parts together with a construction which is strong, efficient
45 and susceptible of long and hard use.

The invention further contemplates the arrangement of the gripper fingers in such a manner as to have a floating support for the same in order that the same may yield
50 slightly to receive stock of varying thick-

nesses without having to adjust the gripper mechanism when the variation of such stock occurs. The gripper mechanism of this invention is susceptible of use with a single sheet of paper or the like as well as with
55 plied material or signatures or sections for books or the like.

The invention contemplates also a rock shaft supported in the rotary carriers which shaft carries the grippers in such manner
60 as to move the grippers into and out of gripping association with the carriers for gripping and releasing sheets and the like, which rock shaft is rocked by a tumbler at one end of the shaft cooperating with curved
65 flanges which are spaced in such a manner as to rock the shaft in one direction when the tumbler engages one of the flanges and to rock the shaft in the opposite direction when the tumbler engages another of the
70 flanges.

The above, other and further objects of the invention will be apparent from the following description, accompanying drawings and appended claims.

An embodiment of the invention is illustrated in the accompanying drawings in the views thereof as follows:

Figure 1 is an end view of a gripper mechanism embodying the present invention.

Figure 2 is a fragmental elevational view of the operative parts of the machine illustrated in Figure 1.

Figure 3 is a sectional view taken substantially in the plain of line III—III of Figure 2.

Figure 4 is a sectional view taken substantially in the plane of line IV—IV of Figure 2.

Figure 5 is an enlarged fragmental partial sectional view of a gripper and the compensating means for the same.

The gripper mechanism illustrated is arranged to be operated in connection with a feed table not shown by which sheets or sections or signatures are delivered to the gripper mechanism by tapes or the like.

The illustrated embodiment of the invention comprises side frame members 1 and 2 which frame members have rearwardly

extending portions 3 and upwardly extending portions 4.

A shaft 5 is journalled in the side frame members 1 and 2 and is provided at one end preferably outwardly of the frame member 2 with a driving gear which is driven in any suitable manner from any suitable source of power, for continuously rotating the shaft 5.

10 A cam 6 is fast on the shaft 5 at the other end thereof, said cam having surfaces 7, 8, 9 and 10 as indicated in Figure 1 for purposes to be hereinafter explained.

15 Rotary carriers are fast on the shaft 5 for receiving paper from the feed mechanism and conveying the same through a portion of the travel of the carriers. There are three such carriers shown, 11, 12 and 13, although more or less may be utilized depending of course on the size of the gripper mechanism desired.

20 The carriers are substantially the same construction and it is believed that a description of one will suffice for all.

25 The carriers consist of a wheel 14 having a hub 15 which is keyed or otherwise fastened to the shaft 5. The wheel 14 has a flat peripheral portion 16 with a portion thereof as at 17 of greater width than the 30 balance of the periphery 16. The widened portion 17 forms less than half of the periphery of the wheel.

35 The carriers are arranged to rotate in the directions indicated by the arrows in the various figures, for instance, counterclockwise rotation in Figure 3 and clockwise rotation in Figure 1.

40 The lead end of the widened peripheral portion 17 indicated at 18 cooperates with a gripper finger in forming a gripping surface so that the sheet, signature, pile or the like may be gripped between the end 18 of the widened peripheral portion 17 of the carrier and a gripper finger whereby the 45 sheet, signature, pile or the like may be moved by the carriers in the manner hereinafter described.

45 A rock shaft 19 passes through and is carried by the several rotary carriers 11, 12 and 13 and is spaced radially from the shaft 5, being revoluble with the carriers. The shaft 19 extends beyond the outer surfaces of the outer carriers.

55 Adjacent each of the carriers on the rock shaft 19 is a hub 20 having outwardly extending spaced ears 21, 22. The hub 20 is fastened to the rock shaft 19. The hub 20 is arranged on the rock shaft 19 with respect to its carrier on the same side thereof 60 as the widened peripheral portion 17.

A gripper arm 23 is freely mounted on the rock shaft 19 between the hub 20 and the adjacent carrier lying between the hub and the carrier so that the gripper finger 24 85 thereof will cooperate with the gripping end

18 of the widened peripheral portion 17 of the carrier.

The gripper arm 23 is provided with a lateral extension 25 which when the parts are assembled lies between the ears 21 and 22 of the hub 20. The extension 25 is of less thickness than the space between these ears so as to allow play of the extension between the ears. The gripper finger 24 is secured by means of screws or like attaching means 26 to the arm 23.

70 The ear 21 is preferably of greater depth than the ear 22 and is provided with a threaded bore 27 (Figure 5) in which is placed a spring 28 having one end resting against the extension or lug 25 on the gripper arm 23 and the other end resting against an adjusting screw 29 threaded into the bore 27 for adjusting the pressure of the spring 75 against said lug or extension. The effect of such spring is to normally urge the extension or lug 25 towards or against the outer ear 22 on the hub 20 and thus maintain the gripper finger 24 in tight engagement with the gripper end 18 of the lateral peripheral portion 17 and of any material that there 80 may be therebetween fed from the feeding mechanism.

85 A tumbler 30 is fastened to one end of the rock shaft 19 outwardly of the endmost 90 rotary carrier 11. The tumbler consists of a substantially T-head 31 having rollers 32 and 33 extending laterally therefrom in spaced relation one on each side of the axis of the rock shaft 19 and projecting away 95 from the end carrier 11.

95 A plate or integral part 34 of the end frame member 1 is provided with a plurality of curved axially and circumferentially spaced portions for cooperation with the tumbler 30.

100 There are two such flanges shown. One flange 35 is arranged at the margin of the plate or like structure 34 and extends for some distance about the periphery of the 105 same, preferably not to exceed 180°.

110 Another such flange 36 is formed as a part of the plate 34 and is arranged radially inwardly of the flange 35 and in spaced circumferential relation with respect to the 115 same. The curved flange 36 is of less extent than the flange 35.

120 A shaft 37 is suitably supported in the rear extension 3 of the frame members and carries a plurality of tape wheels 38 which support tapes 39 for delivering sheets, signatures, piles or the like to the gripper mechanism of this invention.

125 Bars 40 extend forwardly from the tape 39 and terminate adjacent the gripping area of the carriers.

130 The uprights 4 carry a shaft 41 which in turn has fastened to it forwardly extending stop members 42 which stop members have end portions 43 for straddling the bars 40 130

and to serve as stops for the material fed from the feeder tape 39. The shaft 41 is oscillated so as to move the stops 42 into and out of stopping position by means of an arm 44 fastened at one end of the shaft and oscillated by means of a sliding link 45 which is pivoted at 46 to the arm 44. The lower end of the link 45 is stirrup shaped having legs 47 and 48 to pass over the end of the shaft 5 adjacent this end of the machine. A roller 49 is secured on a stud 50 passing to the link 45 and rolling on the cam 6, moving the link 45 in accordance with the engagement of the roller 49 and the cam surfaces 7, 8, 9 and 10 of said cam member.

A spring 51 is connected at one end to the lever 44 and at the other end to a portion of the frame member 1 for normally urging the lever 44 downwardly in order to maintain at all times the roller 49 in engagement with the cam member 6.

A cross rod 52 is connected to the upper ends of the uprights for strengthening the machine.

The curved or arcuate flange 35 is so disposed that when the rotary carriers 11, 12 and 13 are rotated the roller 33 of the tumbler 30 will strike the entering end of the flange whereupon continued rotation of the carriers will move the tumbler about the roller 33 as a center and oscillate the rock shaft in clockwise rotation as viewed in Figures 3 and 4, that is, in a direction to grip material delivered to the carriers by the tapes 39. The stop heads 43 are so positioned that the material is stopped in such manner that the grippers 24 engage the front edge of the material between the stops and sufficiently far back from the front edge to secure a firm grip of the sheet, signature, pile or the like. The moment the grippers 24 grip the sheet, the cam surface 9 of the cam member 6 engages underneath the roller 49 to move the link 45 upwardly thus swinging the stop 42 out of the path of movement of the sheet so that the carriers 11, 12 and 13 may take with the same the gripped sheet. The roller 33 by this time, that is by the time the T-head of the tumbler has turned underneath into the dotted line position shown at the left of Figure 4, rides on the inner surface of the arcuate or curved flange 35. The parts are so arranged that the engagement of the roller 33 with the under surface of this flange 35 will cause the grippers 24 to tightly grip the sheet or file or signature or the like to positively move the same with the carriers. Any variation in the thickness of the sheet is compensated for by the floating arrangement of finger arms 23 and the springs 28.

This condition prevails until the carriers are rotated so that the roller 33 leaves the lower end of the flange 35 whereupon re-

straint is removed from the tumbler and the grippers then fall away from gripping engagement with the sheet and the sheet is then dropped underneath the shaft 5 onto another conveyor or into a suitable receptacle not shown. Continued rotation in counterclockwise direction as viewed in Figures 3 and 4 then brings the roller 32 against the front end of the second flange member 36 whereupon the roller 32 serves as a fulcrum and the T-head 31 is turned about until the roller 32 rides on the outer surfaces of the flange 36. This oscillates the rock shaft in the opposite direction moving the gripper fingers to fully opened position which is that shown in Figures 3 and 5.

Continued rotation of the shaft 5 then brings the tumbler in the position shown in Figure 4 in full lines, that is with the roller 33 against the leading end of the flange 35 whereupon the T-head 31 is tilted about the roller 33 as a center and the gripper fingers caused to close against the gripping edge 18 of the lateral peripheral portion 17 of the carriers for gripping the next sheet.

All of the parts are strongly constructed so as to withstand long and continued service at high speed. The only thing in connection with this mechanism which is likely to need replacement or adjustment is the spring 28 in the floating connection of the finger arms which replacement or adjustment may be made with a relatively short loss of time as the parts are easy to reach and susceptible of quick replacement or adjustment.

Such gripping mechanism is sturdy, rigid and accurate in operation and may be operated at high speed irrespective of the class of stock being fed to the same.

While the carriers illustrated and described are skeleton cylinders, it is of course understood that any kind of cylinder or similar structure can be used, such, for instance, as a solid printing cylinder, in connection with this invention.

The gripper mechanism of this invention could be applied to a two revolution press by making the plate 34 axially movable into and out of position for actuating the tumbler.

The invention has been described herein more or less precisely as to details, yet it is to be understood that the invention is not to be limited thereby as changes may be made in the arrangement and proportion of parts and equivalents may be substituted without departing from the spirit and scope of the invention.

The invention is claimed as follows:

1. A gripper mechanism including in combination rotary carriers, grippers on said carriers, a tumbler for actuating said grippers, and curved flanges spaced circumferentially and radially from each other for

- tilting said tumbler in opposite directions.
2. A gripper mechanism including in combination a plurality of rotary carriers, grippers on said carriers, said grippers being connected for simultaneous movement, a single tumbler on said connection, and curved surfaces, spaced circumferentially and radially from each other and sequentially engageable by said tumbler for moving said grippers successively into gripping and releasing positions.
3. A gripper mechanism including in combination co-axial rotary carriers having flat peripheries, a rock shaft passing through and supported in said carriers parallel to and radially spaced from the axis thereof, gripper fingers on said rock shaft movable into and out of gripping engagement with laterally extending portions of said flat peripheries, a tumbler on one end of said rock shaft having rollers thereon on opposite sides of the rock shaft axis, arcuate surfaces spaced radially and circumferentially and alternately engageable by said rollers for tilting said tumblers successively in opposite directions for moving said grippers into and out of gripping contact with said laterally extending peripheral portions.
4. A gripper mechanism including a plurality of co-axial rotary carriers, a rock shaft extending through and supported in said carriers, gripper fingers on said rock shaft, a T-shaped tumbler on one end of said rock shaft, arcuate surfaces spaced radially and circumferentially and successively engageable by said tumbler as said carriers are rotated, one of said surfaces disposed with an end in the path of movement of one of the ends of the T-shaped tumbler to tilt the same in one direction, and another of said surfaces disposed with an end in the path of movement of the other end of said T-shaped tumbler to tilt the same in the opposite direction.
5. A gripper mechanism including a plurality of co-axial rotary carriers, a rock shaft extending through and supported in said carriers, gripper fingers on said rock shaft, a T-shaped tumbler on one end of said rock shaft, two arcuate surfaces spaced radially and circumferentially and successively engageable by said tumbler as said carriers are rotated, one of said surfaces disposed with an end in the path of movement of one of the ends of the T-shaped tumbler to tilt the same in one direction, and the other of said surfaces disposed with an end in the path of movement of the other end of said T-shaped tumbler to tilt the same in the opposite direction, said tumbler riding on the surface throughout the length of the same to prevent rocking movement of said rock shaft.
6. A gripper mechanism including in combination rotary carriers, grippers associated with said carriers, a single instrumentality for moving said grippers simultaneously into and out of gripping position, a plate having curved surfaces spaced circumferentially and radially from each other and projecting outwardly from the same side of said plate and successively engageable by said instrumentality for actuating the same to move said grippers in the manner stated.
7. A gripper mechanism with a rotary carrier, grippers on said carrier, a tumbler for actuating said grippers, and a plate having curved flanges spaced circumferentially and radially from each other for tilting said tumbler in opposite directions.
8. A gripper mechanism including in combination a rotary carrier, grippers on said carrier, said grippers being connected for simultaneous movement, a single tumbler on said connection, and curved surfaces spaced circumferentially and radially from each other sequentially engageable by said tumbler for moving said grippers successively into gripping and releasing positions.
9. A gripper mechanism including in combination a rotary carrier, grippers associated with said carrier, a single instrumentality for moving said grippers simultaneously into and out of gripping position, and curved surfaces spaced circumferentially and radially from each other and successively engageable by said instrumentality for actuating the same to move said grippers in the manner stated.
10. A gripper mechanism including a rotary carrier having a lateral extension as a part of its periphery, a rock shaft passing through said carrier in spaced relation to the carrier axis, a gripper finger on said shaft movable into and out of gripping engagement with said lateral extension as said shaft is rocked, said finger having limited floating movement with respect to said shaft to compensate for variations in thicknesses of signatures delivered to said carrier, means for rotating said carrier and means for rocking said shaft.
- In testimony whereof I have hereunto subscribed my name at Chicago, Cook County, Illinois.
- CHARLES L. MOYER.
